ALBERT H. STEBBINS, OF LOS ANGELES, CALIFORNIA.

CONCENTRATOR.

Application filed July 2, 1926. Serial No. 120,217.

This invention relates to table concentrators and more particularly to the construction of concentrator decks.

In the concentrator decks now extensively used for treating materials in a dry condition, the deck surface is supported at a transverse inclination to cause the tailing to flow laterally over the deck surface toward the lower or tailing discharge side of the deck, and the riffles or channels upon the deck surface slope upwardly toward the concentrate wall to direct the concentrates away from the lower side of the deck as they travel along the riffles. In other words, the construction of the concentrator decks now extensively used is such that the riffles extend diagonally over the deck surface toward the concentrate wall at an inclination to the path of deck movement and the concentrates are forced against and along the guiding riffles by the deck movement.

The construction of the present invention differs from that above mentioned in that in the present construction the concentrates are not forced against the side wall of the channel over which the tailings escape as heretofore, but are forced away from this side of the channel.

One important feature of the present invention therefore resides in a concentrator deck having the riffles or channels arranged so that they extend across the path of deck movement in a direction to cause the movement to work the concentrates away from the discharge side of the channels.

Another feature of the invention resides in the construction of the channels whereby the floor portion of each channel is given a downward slope in a direction to direct the materials in the channel away from the discharge side thereof.

As a result of the features just mentioned, the concentrates traveling along a channel will work down under the tailing away from the discharge side of the channel while the tailings displaced by the concentrates are forced upwardly and toward the discharge side of the channel. It is desirable to crowd these tailings out of the channels, and another feature of the invention resides in the construction whereby the size of the channels is gradually decreased in the direction in which the materials travel. As a result the tailings are gradually forced laterally out of the channels, thus effecting the desired separation of the materials.

Other features of the invention and novel combination of parts in addition to the above will be hereinafter described in connection with the accompanying drawings which illustrate good practical forms of the invention.

In the drawings:

Fig. 1 is a plan view of a table concentrator provided with a deck constructed in accordance with the present invention;

Fig. 2 is a side elevation of the table concentrator of Fig. 1;

Fig. 3 on an enlarged scale is a sectional view taken on the line 3—3 of Fig. 1;

Fig. 4 is an end view of the material discharge end of the deck shown in Fig. 1;

Fig. 5 is a perspective view of a modified deck construction embodying features of the present invention;

Fig. 6 is a sectional view taken on the line 6—6 of Fig. 5;

Fig. 7 is a top plan view of a deck shaped the same as in Fig. 5 but shows the deck surface as provided with grooved channels 80 in place of the riffles of Fig. 5;

Fig. 8 is a perspective view of a portion of the deck surface of Fig. 1, showing the construction of one of the channels;

Fig. 9 is a similar view of a portion of the deck of Fig. 7; and

Fig. 10 is a transverse sectional view through another modified deck construction.

In the embodiment of the invention shown in Figs. 1 to 4 inclusive the concentrator deck 10 is mounted upon the carriage 11 which carriage is supported by a frame of any suitable construction so that the carriage may be moved back and forth in the direction of its length.

The deck supporting frame shown is formed of the uprights 12 to which the longitudinally extending rails 13 are secured, and the carriage 11 is supported upon the frame for movement in the direction of its length by the balls or rollers 14 which are mounted in the grooved bearing blocks 15 secured to the supporting frame, and the upper portion of each ball enters a similarly grooved bearing block 16 secured to the under face of the carriage.

The concentrator deck 10 is supported at a transverse inclination as usual, and to this end one side of the concentrator deck is secured to the carriage 11 by the hinges 17 while the opposite side of the deck is supported in spaced relation to the carriage by

adjustable bolts or the like 18 (see Fig. 3). The materials to be treated may be supplied to the deck surface by the hopper 19. If air is employed in effecting the separation of 5 the materials upon the deck surface, air under pressure may be delivered to the air chamber 20 of the deck by the fan 21, the discharge portion of which fan is connected to the hood 22 leading to the chamber 20 10 below the deck surface.

As above stated, one of the important features of the present invention resides in the construction of the channels provided upon the deck surface. These channels 23, 15 as shown in Figs. 1 to 4 inclusive, are formed by giving the deck surface the stepped construction best shown in Fig. 3, wherein it will be seen that each channel has a floor portion 24 and an upstanding wall 25, and 20 it should be noted that in the construction shown in Fig. 3 the floor portion 24 of each channel slopes in a downward direction towards the upstanding portion 25 of its channel. In other words, the slope of each floor 25 portion 24 is such that the materials will tend to slide across the floor portion under the influence of gravity away from the lower side of the deck; this construction is desirable as it tends to work the concentrates 30 away from the discharge side of each channel.

The channels 23 are preferably so constructed that they gradually decrease in width and in depth in the direction in which 35 the materials travel along the same. This is desirable because by forming the channels so that they grow more shallow as they approach the discharge end of the deck, they gradually crowd out the lighter materials or tailings which have been displaced by the 40 concentrates lying near the bottom of the channels. The formation of the channels 23 is such that the material receiving surfaces 26 are provided near the discharge end of the channels, and the width of these surfaces 26, as will be apparent from the drawings, 45 is gradually increased in the direction in which the materials travel along the channels.

50 The upper side of the deck 10 is preferably provided with a concentrate wall 27 having the usual buffer blocks 28 against which the concentrates are directed by the channels terminating along this wall; the 55 arrangement being such that the materials directed against the concentrate wall by the channels will work downwardly under the influence of the deck inclination from one channel to another for retreatment. At the 60 lower side of the deck may be provided the usual inclined wall 29 which extends in a diagonal direction from the feed hopper 19 to the lower or discharge side of the deck.

65 It may be found desirable to feed the materials to the portion of the deck surface ly-

ing adjacent the feed hopper in sufficient quantity to cause the materials to fill up the channels and to pile up to some extent upon the deck surface, in which case it is desirable to provide means for preventing the materials from flowing to rapidly transversely of the deck. This is accomplished, in accordance with the present invention, by providing the portion of each channel lying 70 near the feed hopper with an upstanding riffle or wall 30. These riffles may extend lengthwise of the channels any desired distance and are preferably reduced in height in the direction in which they extend, as best shown in Fig. 8, wherein it will be seen 75 that the riffles gradually taper downwardly toward the floor portion of the channels until they entirely disappear, and these riffles may be formed by extending the upright wall 25 of each channel upwardly beyond the adjacent floor portion, as will be apparent from Fig. 3.

As above indicated, another feature of the present invention resides in the arrangement whereby the channels extend across the path 80 of deck movement in a direction to cause the concentrates within a channel to work away from the discharge side of the channel. This is accomplished, in the construction 85 shown in Figs. 1 to 4 inclusive, by mounting the deck 10 upon its carriage 11 so that the channels 23 slope downwardly across the path of deck movement as they extend from the material receiving end towards the discharge end of the deck. This will be apparent 90 from Fig. 1 wherein the broken line *a—a* indicates the path of deck movement, and the line *b—b* indicates the inclination of the channels 23 with respect to the deck movement, and it will be seen that the line *b—b* crosses the line *a—a*. The angle 95 formed by these two lines may be made as great as desired, but a very slight angle will be sufficient to cause the movement imparted to the deck to gradually work the materials 100 in the channels away from the discharge side thereof, and back towards the upstanding wall 25 of the channels. As above pointed 105 out, the tendency of the materials within a channel to work away from the discharge side thereof may be increased by sloping the floor portion 24 of each channel so that the 110 materials will tend to slide across the floor portion away from the discharge side of the channels.

115 As a result of the deck construction described it will be seen that as the materials travel lengthwise of the deck within a channel 23, the concentrates will gradually work 120 down towards the bottom of a channel. This will force the tailings upwardly, and since the size of each channel gradually decreases as it approaches the discharge end of the deck, the tailings within the channel will be 125 gradually crowded out of the channel to flow 130

over the side thereof towards the lower side of the deck. In this manner the tailings are forced out of the channels very effectively, and as a result each channel acts as an individual concentrator, while the concentrate wall 27 and buffer blocks act to reclean and rework the products directed against the concentrate wall to remove such tailings as may not have been worked out of the concentrators.

As the tailings are crowded out of first one channel and then another they will gradually work downwardly across the inclined deck until they are discharged from the lower side thereof over the discharge board 31 while the concentrates will be delivered by the channels to the hopper 32 at the end of the deck.

The material receiving spaces 26 lying between the channels near the discharge end of the deck do not constitute waste or useless spaces, but they help to effect the separating operation. This is due to the fact that the fine values which may work out of a channel onto an inclined surface 26 will move transversely of such surface towards the next channel below much more slowly than will the larger tailings which may work out of a channel onto said surface. It will therefore be seen that since large particles tend to roll or slide along an inclined surface much more rapidly than do fine dust like particles, the inclined surfaces 26 will help to promote the separation of the values from the tailings in the manner just pointed out.

The deck supporting carriage 11 may be supported in a horizontal plane as shown, or, if desired, it may be inclined in the direction of its length so that it will slope either downwardly or upwardly in the direction in which the materials travel over the deck surface. In some cases it may be desirable to impart a slight up-hill slope to the entire deck surface in the direction in which the materials travel over the same, while in other cases it may be desirable to impart a down-hill slope to the deck towards its discharge end to promote the travel of the materials lengthwise of the deck. Any suitable operating means may be employed for imparting a progressive movement to the deck, and the means shown to this end consists of an operating cable 33, an intermediate portion of which is secured to the under face of the carriage 11 by the clamping blocks 34. One end portion of the cable 33 extends around a grooved idle sheave 35 which is rotatably supported by the shaft 36, and this portion of the cable extends downwardly from the sheave 35 and has its end secured to a coiled spring 37; the arrangement being such that the tension of the spring 37 will act upon the cable to continuously urge the deck in a right-hand di-

rection viewing Fig. 2. The opposite end portion of the cable 33 is led around a grooved idle sheave 38 and passes from the lower side of this idle sheave about a second grooved sheave 39. The sheave 39 is mounted upon the eccentric 40 which is rigidly secured to the driving shaft 41. The portion of the cable last mentioned is led from the lower portion of the sheave 39 to a bolt or the like 42 which is anchored to the deck supporting frame. The arrangement just described is such that as the eccentric 40 is rotated by its power shaft within the sheave 39 it will move this sheave in an orbital path alternately to tension and slack off the portion of the cable looped about the sheave 39. This will serve to positively pull the deck 10 in a left-hand direction and then release it to move in a right-hand direction under the action of the spring 37, and by varying the tension of the spring the progressive movement imparted to the deck by the operating means just described may be made as energetic as desired.

In the modified construction shown in Figs. 5 and 6 the concentrator deck 43 is secured to the deck supporting carriage 44 by hinges 45 which are disposed diagonally of the carriage. This arrangement is desirable in some constructions because as the deck 43 is rocked about its hinges 45 to vary the traverse slope of the deck the rocking movement will serve also to elevate the discharge end of the deck with respect to the material receiving end thereof. As a result of the construction shown in Fig. 5, adjustment of the deck about the hinges just mentioned will serve to vary the transverse inclination of the deck, and also the longitudinal inclination of the same. The materials to be treated are supplied to the deck 43 by the feed hopper 43^a and the rate at which the materials are delivered to the deck from the feed hopper may be controlled by adjusting the gate 43^b.

In the construction shown in Figs. 5 and 6, the channels or material receiving guideways are formed upon the deck by simply providing the upstanding riffles 46 extending over the deck surface 47, and these riffles may have the same height throughout their length, or they may taper from one end toward the other as desired. The riffles 46 terminate along the concentrate wall 48 in the usual manner as shown.

In the construction shown in Fig. 7 the deck is given the same configuration as in Fig. 5, and is provided with the diagonally disposed hinges 45 but in Fig. 7 the channels 49 are formed with an upstanding wall 50 and a floor portion 51 much the same as in Fig. 1. The channels of Figs. 7 and 9 however do not decrease in width as they approach the discharge end of the deck, and

in order to force out of the channels the lighter materials lying above the concentrates within the channels, the adjustable shearing blades 52 may be provided which are held in the desired position of angular adjustment within a channel by the pivot pins 53. Each channel 49 may be provided with as many shearing blades 52 as is deemed advisable, and these blades may be adjusted to different angles with respect to an edge of the channel to thereby increase or decrease the amount of materials that are directed out of the channel by each blade 52. In the modified construction shown in Figs. 7 and 9 relatively long tapered riffles 54 are provided, as will be apparent from the drawing, but it will be understood that the height and length of the riffles may be varied as desired.

The direction of movement imparted to the modified construction shown in Fig. 7 is indicated by the line $a-a$ of this figure, and it will be noted that the channels 49 slope downwardly across the movement line $a-a$ at a greater angle in the modified construction than in the construction shown in Fig. 1. It will therefore be seen that the progressive movement imparted to the construction of Fig. 7 will act more forcibly than in the construction shown in Fig. 1 to work the materials across the channels away from the discharge side thereof. The riffles 46 of Fig. 5 extend downwardly across the path of deck movement the same as in Fig. 7 so that in all embodiments of the invention shown the movement imparted to the deck is in a direction to work the concentrates back from the discharge side of the channels, to thereby reduce the tendency of the concentrates to escape laterally over the side of a channel with the tailings.

In many cases it will be desirable to employ air under pressure to promote the separation of the materials, and to this end the apertures 55 may be provided within each channel near the feed end of the deck, as shown in Fig. 8, or the apertures may extend lengthwise of a channel throughout a substantial distance, as shown in Fig. 9, but when the apertures extend lengthwise of the channel as shown in Fig. 9 they should decrease in number as they approach the discharge end of the deck as shown.

If desired a deck, embodying the features of the present invention, may be formed of wood, as shown in Fig. 10, wherein the channels 56 are cut in the upper surface of the wooden deck. The floor portions 57 of the channels shown in this figure, it should be noted, lie approximately horizontal instead of sloping away from the discharge side of the channel, as in the construction shown in Figs. 1 and 9. It is therefore desirable, in the construction of Fig. 10, to provide each channel 56 with a riffle 58 extending

throughout the entire length of the channel to retain the materials in the channel.

In some constructions it may be desirable to screen the tailings as they pass off the deck over the discharge board 31, in which case it may be found desirable to secure an apertured screen 59 adjacent the lower side of the deck 10 so that the screen 59 will be operated by the vibratory movement imparted to the deck. As a result of this construction the power imparted to the deck to advance the materials lengthwise of the same will serve also to vibrate the screen 59 to sift or screen the tailings. This screen may be readily supported from the carriage 11 by providing the carriage with the laterally extending screen supporting frame 60.

What is claimed is:—

1. A dry concentrator deck, comprising in combination, a deck supporting frame, a deck mounted upon the frame for vibratory movement and having a deck surface that is supported at a transverse inclination and provided with material receiving channels that slope downwardly across the path of deck movement and each channel being provided with air apertures for the passage of air upwardly through the materials in the channels, a stepped concentrate wall extending along the upper side of the deck and arranged at an inclination to the channels and to the lower side of the deck so that the channels terminate along the concentrate wall, said channels being constructed so that they gradually decrease in width and in depth as they approach the concentrate wall and arranged to provide material receiving surfaces between the channels having the general transverse inclination of the deck surface and which serve to retard the flow of the fine values from one channel to the next, and means for vibrating the deck back and forth along a path that crosses the channels in a direction to work the concentrates away from the discharge side of the channels. 100

2. A dry concentrator deck, comprising in combination, a deck supporting frame, a deck mounted upon the frame for vibratory movement and having a deck surface that is supported at a transverse inclination and provided with material receiving channels that slope downwardly across the path of deck movement and each channel being provided with air apertures for the passage of air upwardly through the materials in the channels, a stepped concentrate wall extending along the upper side of the deck and arranged at an inclination to the channels and to the lower side of the deck so that the channels terminate along the concentrate wall and direct the concentrates against the wall for retreatment, said channels being constructed so that they gradually decrease in width as they approach the concentrate 120 125 130

wall and arranged to provide material receiving surfaces between the channels which increase in width toward the discharge end of the deck and which serve to retard the flow of the fine values from one channel to the next, and means for moving the deck back and forth along a path that crosses the channels in a direction to work the concentrates away from the discharge side of the channels.

3. A concentrator deck, comprising in combination, a deck surface that is supported at a transverse inclination and provided with material receiving channels that extend lengthwise of the deck, a concentrate wall extending along the upper side of the deck and arranged at an inclination to the channels and to the lower side of the deck so that the channels terminate along the concentrate wall and direct the concentrates against this wall for retreatment, said channels being constructed so that they gradually decrease in width and in depth as they approach the discharge end of the deck, and tapered riffles formed along the channels adjacent the material receiving end of the deck and adapted to prevent the materials from flowing transversely of the deck.

4. A dry concentrator deck, comprising in combination, a deck supporting frame, a deck mounted upon the frame for vibratory movement and having a deck surface that is supported at a transverse inclination and provided with material receiving channels that slope downwardly across the path of deck movement, a stepped concentrate wall extending along the upper side of the deck and arranged at an inclination to the channels and to the lower side of the deck so that the channels terminate along the concentrate wall, said channels being constructed so that they gradually decrease in width and in depth as they approach the concentrate wall and arranged to provide material receiving surfaces between the channels having the general transverse inclination of the deck surface and which serve to retard the flow of the fine values from one channel to the next, and means for vibrating the deck back and forth along a path that crosses the channels in a direction to work the concentrates away from the discharge side of the channels.

In testimony whereof, I have signed my name to this specification.

ALBERT H. STEBBINS.
